[57] CLAIM

The ornamental design for a cursor control for computer display, as shown and described.

DESCRIPTION

FIG. 1 is a front perspective view of a cursor control for computer display showing our new design;

FIG. 2 is a top plan view thereof on a reduced scale;

FIG. 3 is a bottom plan view thereof on a reduced scale;

FIG. 4 is a front elevational view thereof on a reduced scale;

FIG. 5 is a rear elevational view thereof on a reduced scale;

FIG. 6 is a left hand side elevational view thereof on a reduced scale;

FIG. 7 is a right hand side elevational view thereof on a reduced scale;

FIG. 8 is a front perspective view of a second embodiment of our new design, it being understood that the second embodiment differs from the first only in the number and configuration of the keys.
